CLAIM

The ornamental design for a spinner fishing lure, as shown and described.

DESCRIPTION

FIG. 1 is a right side elevational view of the first embodiment of the spinner fishing lure showing my new design, with the left side elevational view being a mirror image thereof;

FIG. 2 is a right side elevational view of the second embodiment, with the left side elevational view being a mirror image thereof;

FIG. 3 is a right side elevational view of the third embodiment, with the left side elevational view being a mirror image thereof;

FIG. 4 is a right side elevational view of a fourth embodiment, with the left side elevational view being a mirror image thereof;

FIG. 5 is a right side elevational view of a fifth embodiment, with the left side elevational view being a mirror image thereof;

FIG. 6 is a right side elevational view of a sixth embodiment, with the left side elevational view being a mirror image thereof;

FIG. 7 is a front and side perspective view of the seventh embodiment;

FIG. 8 is a front elevational view thereof; and,

FIG. 9 is a right side elevational view thereof, with the left side elevational view being a mirror image thereof.
